UNITED STATES PATENT OFFICE

2,552,194

POLISHING CONVEYER

Edward C. Lindsay, Compton, Calif., and Gerard M. Hurley, Newton Falls, Ohio, assignors to Standard Steel Spring Company, Coraopolis, Pa., a corporation of Pennsylvania

Application May 2, 1949, Serial No. 90,918

1 Claim. (Cl. 51—76)

1 This invention relates to apparatus for conveying a curved workpiece to be polished past a polishing device or past a series of polishing devices and oscillating the workpiece as it moves past the polishing device so that the workpiece can be polished automatically. The invention will be described herein as applied to the polishing of automobile bumpers but it will be understood that other workpieces can be polished in a similar manner.

In one method now known, curved automobile bumpers are conveyed on an endless table to a position where a polishing device such as a polishing wheel or a polishing belt is located. A workman then presses the bumper against the polishing device and so guides the bumper that the polishing wheel passes over a certain area of the bumper. In accordance with the present invention, this manual manipulation of the bumper in contact with the polishing device is eliminated, means being provided for causing the bumper and the table on which it is mounted to oscillate as they move past the polishing device.

In the accompanying drawings which illustrate two embodiments of our invention—

Figure 1 is a plan view of one embodiment;

Figure 2 is a section taken along the line II—II of Figure 1, on an enlarged scale;

Figure 3 is a plan view of the table on which the bumper is mounted, showing the means for mounting the bumper on the table;

Figure 4 is a plan view illustrating different positions which the bumper and table on which it is mounted assume as they move past a polishing device;

Figures 5A and 5B when placed end to end constitute a plan view of a different embodiment of the apparatus from that shown in Figures 1—4;

Figure 6 is a plan view, on an enlarged scale, of a part of the apparatus shown in Figures 5A, 5B;

Figure 7 is a vertical transverse section, on an enlarged scale, taken on the line VII—VII of Figure 5A; and

Figure 8 is a typical cross-section of the cam, showing the cam follower in chain lines.

Referring more particularly to Figures 1—4, an endless conveyer designated generally by the reference numeral 2 is mounted on a base 3. The conveyer comprises an outer track 4 and an inner track 5 formed of inverted channels. The tracks 4 and 5 are supported from the base 3 by uprights 6 and cross-pieces 7.

A plurality of carriages 10 each having four casters 11 are mounted for movement along the

2 tracks. The carriages are moved by a roller chain 12 which is driven by a driving sprocket 13 driven by a motor 14. The chain 12 passes around a series of idler sprockets 15, the chain being connected to each of the carriages 10, as shown in Figure 2, by means of a pin 16 passing through a roller 17 of the chain, the pins 16 being carried by brackets 18 secured to the under side of carriage 10 by bolts 19. A guide roller 22 mounted in a bearing 23 secured to the carriage 10 cooperates with a guide formed of the angle irons 24 for keeping the carriage on the tracks 4 and 5 when the bumper is pressed against the polishing device.

A table designated generally by the reference numeral 26 and comprising an upper part 26a and a lower part 26b is pivotally mounted on the carriage 10 by a trunnion 27 secured to the carriage and mounted in a bearing 28 secured by bolts 29 to the lower part 26b of the table. The table 26 is supported on the carriage 10 by casters 26c carried by the table. The two table parts 26a and 26b are connected to each other by hinges 30 adjacent one end, as shown most clearly in Figures 2 and 3. Two coil springs 32 are interposed between the upper table part 26a and the lower table part 26b, these coil springs being located adjacent the ends of the table parts which lie opposite the hinges 30. A leaf spring 33 (see Figure 3) also is interposed between the upper table part 26a and the lower table part 26b, this leaf spring lying between the coil springs 32. The leaf spring 33 is secured to the upper table part 26a by a bracket 34, this bracket being located adjacent the middle of the spring. The ends 33a of the leaf spring are curved downwardly to contact with the lower table part 26b. Means is provided to limit the extent to which the springs 32 and 33 force the table parts 26a and 26b apart. This means comprises bolts 36 passing through openings in the table parts 26a and 26b, the bolts being provided with nuts 37 which when tightened draw the two table parts together against the tension of the springs. The arrangement is such as to provide a resilient mounting between the upper and lower table parts 26a and 26b so as to resist any tendency of the polishing device to gouge the bumper during polishing. Also the hinged mounting enables the upper table part 26a to be tilted relative to table part 26b so as to present different portions of the bumper 40 to the polishing devices.

The means for mounting a bumper 40 on the upper table part 26a is shown particularly in Figures 2 and 3. Three angle irons 41 are secured

cured to the table part 26a. A plate 42 is adjustably secured to each of the angle irons 41 by means of a bolt and nut 43, the bolt passing through slots 44 formed in the angle irons 41 and plates 42. The outer ends 42a of the plates 42 fit against the inner surface of the bumper. Two rods 46 slidably mounted in guides 47 are eccentrically pivotally connected at their inner ends 48 to a disc 49 which is pivoted at 50 to the table part 26a and provided with a handle 51 for rotating it. When the handle 51 is rotated in a counterclockwise position from that shown in Figure 3, the rods 46 are forced outwardly so that the outer ends 46a of the rods contact the inner surface of the bumper and lock it in position on the table.

The lower table part 26b has an arm 54 secured to it, the arm carrying a cam follower 55 which in the embodiment shown is a roller. This cam follower cooperates with a cam 56 which extends lengthwise of the conveyer. The cam is of such shape that it causes the table 26 and the bumper 40 supported thereon to oscillate relative to the carriage 10 on the trunnion 27 as the carriage moves past each of a series of polishing wheels 60.

Referring more particularly to Figures 1 and 4, the bumper 40 is shown in three different successive positions. In these figures the carriage 10 and work supporting table 26 move to the left as shown by the arrow 62. The first position of the bumper 40 with respect to the polishing wheel 60 is shown in full lines in Figure 4, the second position being shown in chain lines, and the third position being shown in dash lines. Thus as the cam follower 55 moves successively through the points 63, 64 and 65 on the cam 56, the table 26 is oscillated about the pivot 27 so as to present successively to the polishing wheel 60 the points 63a, 64a and 65a of the bumper.

In using the apparatus a bumper may be secured to one of the tables 26 at a loading station A of the conveyer. It then moves to the left as shown in Figure 1 and is polished successively by the polishing wheels 60, three of which are shown, each of the polishing wheels being arranged to polish a different portion of the vertical contour of the bumper. It is to be understood, however, that each of the polishing wheels 60 traverses a path from the point 63a to the point 65a of the length of the bumper. After the bumper has been polished by the wheels 60 and is passing around the left-hand end B of the conveyer, the table 26 is turned manually in a counterclockwise direction until the bumper assumes the position shown at C. The bumper then moves along the conveyer past a series of polishing wheels 68 located on opposite sides of the conveyer which polish the ends 69 of the bumper. The bumper is then unloaded from the conveyer at station D.

The embodiment illustrated in Figures 5-8 is generally similar to that previously described but differs in that the cams which guide the tables and bumpers mounted thereon in their movement past the polishing devices are located above the track instead of being alongside of the track, and secondly in that means is provided for automatically turning the bumpers after their intermediate portions have been polished by one series of polishing devices, to a position which presents the inturned ends of the bumpers to a series of other polishing devices.

Referring more particularly to Figures 5-8, the carriage 70 is mounted on casters 71 which run

on tracks 72 and 73, the carriage being provided with a roller 74 fitting in a guide 75. The carriages are driven by a chain in the manner described in connection with Figures 1-4. A table 76 having an upper part and a lower part hinged together at 77 is pivotally mounted on a trunnion 78 carried by the carriage so that the table can oscillate or turn relative to the carriage. The bumper 79 is secured to the table in the manner previously described.

The movement of the bumper supporting tables 76 in their travel along the tracks is governed by a plurality of overhead cams and two cam followers which are secured to the table and cooperate with the cams individually and successively. One cam and cam follower guides the table during its travel past a series of polishing devices, the second cam being inoperative at this time, and thereafter the second cam follower becomes operative to cause the table to turn, the first cam and cam follower being inoperative at this time.

A first cam follower 80, which in the embodiment shown is a roller, is mounted on the upper end of a bracket 80a which is carried at its lower end on the table 76. The cam follower 80 cooperates with a cam 81 which is located above the tracks and tables and is supported by any suitable means, not shown. The cam 81 and cam follower 80 guide the tables and bumpers 79 mounted thereon in their travel past a series of polishing devices 82 shown in Figures 5A, 5B. During this portion of the travel of the bumpers they are oscillated so that the intermediate portion of each bumper is presented to the polishing wheels as described in connection with Figures 1-4. The oscillation of the table 76 on the trunnion 78 relative to the carriage 70 is accomplished because of the curvature of the cam 81. In Figures 5A, 5B the heavier line 85 designates the center line of the various cams and the lighter line 86 designates the path of travel of the trunnion 78. A second cam follower 87 is mounted on the upper end of a bracket 88 having its lower end secured to the table 76. The cam follower 87 cooperates with a turning cam 89 (see Figure 5B) to turn the table counterclockwise substantially 90° so that the ends 79a and 79b of the bumper will be in a position to be polished by a series of polishing devices 90 and 91 located on opposite sides of the track.

The operation may be carried out in the following manner. A bumper 79 is loaded on to a table 76 at the loading station E and is secured to the table. The tables are moved by the chain 92 passing around sprockets 93, one of which is driven by a motor 94. The table then moves past a series of polishing devices 82 which polish the intermediate portion of the bumper, the bumper taking the various positions shown in Figures 5A, 5B as it passes each of the polishing devices 82. During the travel of the table past the polishing devices 82 it is guided by the cam 81 and cam follower 80, the cam follower 87 being inoperative at this time.

When the table has passed the polishing devices 82 and is approaching the left-hand end of the conveyer shown in Figure 5B, it is turned by the turning cam 89 and cam follower 81. The turning cam 89 extends at an angle to the track and has its leading end 89a spaced from but in substantial transverse alignment with the following end 81a of the cam 81. The following end 89b of cam 89 is connected to the leading end 95a of a second cam 95. As the cam follower

80 leaves the cam 81, the cam follower 87 contacts the turning cam 89 and causes the table to be turned counterclockwise through substantially 90°. The table then continues its travel around the left-hand end of the conveyer shown in Figure 5 so that when it reaches the polishing devices 90 it is in a position for such polishing devices to act on the ends 79a of the bumpers. The table then continues its travel and shortly before it reaches the first of the polishing devices 91 the cam follower is guided by an outwardly curved portion 95b of the cam 95 so as to oscillate the table and bumper so that the end 79b is in a position to be contacted by the polishing devices 91.

After the bumper has passed the last of the polishing devices 91, the cam follower 87 leaves the following end 95c of the cam 95 and at the same time the cam follower 80 contacts a turning cam 96 which turns the bumper in a clockwise direction so that it can be removed easily from the conveyer at station F. The table then moves on to the loading station E where another bumper is loaded on to it.

The invention is not limited to the embodiments which have been described merely for purposes of illustration, but may be otherwise embodied or practiced within the scope of the following claim.

We claim:

Apparatus for conveying a curved workpiece to be polished past and in contact with a polish-

ing device, which comprises a track, a carriage located above said track and means for moving it along the track, a table pivotally mounted on top of the carriage, the table comprising an upper part and a lower part hinged together adjacent one end, the opposite end of said upper and lower parts having resilient means interposed between them, means on said upper part for rigidly mounting the workpiece thereon, a sinuous cam extending lengthwise of the track, and a cam follower connected to said table and cooperating with said cam for oscillating said table and the workpiece mounted thereon relative to said carriage as they move past the polishing device.

EDWARD C. LINDSAY.
GERARD M. HURLEY.
